UNITED STATES PATENT OFFICE.

PERCY TATCHELL, OF LONDON, ENGLAND.

SAIL-BOOM.

No. 879,986.

Specification of Letters Patent.

Patented Feb. 25, 1908.

Application filed July 2, 1906. Serial No. 324,484.

To all whom it may concern:

Be it known that I, PERCY TATCHELL, a subject of the King of Great Britain, residing at 73 Holland Park, in the county of 5 London, England, gentleman, have invented certain new and useful Improvements in Sail-Booms, of which the following is a specification, reference being had to the drawings hereunto annexed and to the figures and 10 letters marked thereon—that is to say—

The invention relates to improvements in or connected with sail-booms and the object thereof is to obtain a suitable lateral curvature in the boom and at the same time 15 to brace the same in such manner that it will be strengthened or stiffened.

It is now a generally accepted theory that a certain amount of belly in a mainsail of fore and aft vessels is advantageous in certain 20 conditions of wind, and when sailing to windward, and the best results are obtained by varying this belly according to the strength of the wind and diminishing it as the wind increases in force. This has to 25 some extent been accomplished by cutting the sail rather full at the fore part or luff so as to obtain a certain amount of belly or flow which should, it is generally conceded, take the form of a parabolic curve.

Now according to the present invention 30 the sail is cut with little or no belly or flow and is laced or otherwise fastened to the boom and the necessary belly or curve is imparted to the sail by bending the boom 35 laterally to the required degree to give the best results under the conditions of wind prevailing.

In the accompanying drawings, Figure 1 is a side elevation of the main boom and part 40 of the mast of a vessel; illustrating the application of the present invention to the main boom and showing the same in its normal condition. Fig. 2 is a plan thereof. Fig. 3 is a transverse section taken on the line 1—1 45 of Fig. 1. Fig. 4 is a plan of Fig. 3. Fig. 5 is a transverse section taken on the line 2—2 of Fig. 1. Fig. 6 is a transverse section taken on the line 3—3 of Fig. 1. Fig. 7 is a transverse section taken on the line 4—4 of Fig. 1. 50 Fig. 8 is a similar view to Fig. 2 but showing the boom in its bent condition. Fig. 9 is a similar view to Fig. 8 illustrating a slight modification. Fig. 10 is a transverse section taken on the line 5—5 of Fig. 9. Fig. 11 is a 55 transverse section taken on the line 6—6 of Fig. 9. Fig. 12 is a transverse section taken

on the line 7—7 of Fig. 9. Fig. 13 is a similar view to Fig. 8 illustrating a further slight modification. Fig. 14 is a side elevation of part of Fig. 13. Fig. 15 is a similar view to Fig. 1 illustrating a further modification. Fig. 16 is a plan thereof but showing the boom in its bent condition. Fig. 17 is a similar view to Fig. 1 illustrating the application of the invention to a balanced lug sail and Fig. 18 is a plan thereof showing the boom 60 in its bent condition.

In the several figures like parts are indicated by similar letters of reference and Figs. 3 to 7 and 10 to 12 are drawn to an increased 70 scale with respect to the other figures of the drawings.

Referring to Figs. 1 to 8, *a* represents the deck of a vessel, *b* represents the mast and *c* represents the main boom. The boom *c* is 75 assumed to be solid and to be constructed of wood but it will be obvious that it might be hollow and if desired constructed of metal or other suitable material and it may be of any suitable transverse section. 80

In the example given the boom is of a gradual taper from end to end, the smaller and lighter part being at the fore end or neck, and the larger and heavier part at the outer extremity, being at the after end, and it is 85 shown to be of a flattened section, as that is preferable for the purpose of the invention, although it may be of any other suitable section. Transversely of the boom *c* and near or toward the fore end or neck thereof are arranged so as to project horizontally from each side thereof two struts *d* preferably carried by a band or collar *d'* clamped around the boom in the well known manner or the struts *d* might be fixed with the boom *c* in 90 any other suitable manner and the extremities of the struts *d* are forked or notched, and if desired, furnished with sheaves or runners *d''* as shown. Or instead of employing only one pair of struts *d* two pairs might be provided as hereinafter shown and described with respect to the subsequent figures or more than two pairs of struts might be employed if desired. 95

In connection with the strut *d* on each side 100 of the boom *c* is employed a stay *e* consisting of a length of wire rope or it might be of other rope, chain, rod metal or the like and this stay *e* is by one end made fast to an eye *f'* arranged at one side of the boom *c* and carried 105 by a cap *f* or it might be any other suitable fitting upon the after end of the boom *c*. The 110

- stay e is then carried across the sheave or the like d^2 at the extremity of the strut d on one side of the boom and the other end thereof is made fast to a tackle or purchase g fastened 5 to an eye h' carried by a fitting h upon the fore end of the boom c . The corresponding stay e upon the opposite side of the boom is similarly arranged and provided with similar tightening means and similarly operated.
- 10 By hauling upon the fall g' of the tackle g on one side of the boom and somewhat slackening the other fall any desired curvature within certain limits may be given to the boom the preferred curvature being parabolic and it
- 15 may be fixed at that curvature by belaying the fall g' of the tackle upon a cleat a' fastened to the deck a while by subsequently and similarly tightening the stay e on the other or convex side of the boom c the latter 20 will be efficiently braced or stiffened and a strong support given thereto.
- The effect of the curvature of the boom will be to impart the required fullness, hollow or belly to the sail at or near the luff so 25 that theoretically its propulsive power will be improved. When the vessel goes about on another tack the opposite curvature must be given to the boom c by manipulating the tackles g in the manner hereinbefore de-
- 30 scribed.
- In the example given at Figs. 9 to 12 the boom c is formed for part of its length of a cross shape section in order to give additional strength thereto and instead of providing the 35 boom with one pair of struts d two pairs thereof are employed. The tightening devices in this case are shown to consist of rigging screws g of the ordinary character which are manipulated in the ordinary way.
- 40 In the example given in Figs. 13 and 14 the boom c is assumed to be of similar section to that hereinbefore shown and described with respect to Figs. 1 to 7 but in this case the ends of the stays e are led over guide pul-
- 45 leys or sheaves h^2 carried by the fitting h under guide pulleys h^3 upon the deck a and thence to a winch g fixed to the deck a and provided with the usual pawl g^2 so that by turning the winch in either direction one stay 50 e will be tightened and the other slackened in the desired manner. In this case rigging screws g^* are interposed in the length of the stays e to afford an adjustment thereof with relation to the winch g .
- 55 In the example given at Figs. 15 and 16 the arrangement is substantially the same as that lastly hereinbefore described but a further modification in the means of hauling on the stays e is shown. The ends of the stays e 60 are in this case as in the last preceding example passed around guide pulleys h^2 h^3 the latter being fixed upon the floor a^2 of the boat but instead of being led to a winch they are passed around guide pulleys or sheaves h^3 65 also fixed upon the floor a^2 of the boat and

fastened at g^3 to a lever g at one end mounted upon a pivot g^4 carried by the floor a^2 of the boat or it might be in other convenient position and working over a segmental rack g^2 adapted to fix the lever g in any desired position. By moving the lever over the rack g^2 in one direction or the other one, stay e will be tightened and the other slackened in a similar manner to that described with respect to the last preceding example.

70 In the example given at Figs. 17 and 18 the invention is shown applied to the boom of a balanced lug sail. The tackles g in this case are dispensed with and the ends of the stays e are passed around guide pulleys or sheaves h^2 upon the boom c thence over similar pulleys or sheaves h^{2*} upon the boom and thence under guide pulleys or sheaves h^3 upon the deck a into a convenient position for hauling and tightening by hand or otherwise.

75 Although the invention has been hereinbefore described in connection with the main boom of a sailing vessel it will be understood that it is also applicable to other spars where 80 a curve or belly to the sail would be an advantage and it will also be understood that the curved spar is useful for other purposes such for example as the construction of the framework of flying machines.

85 90 95 By the means hereinbefore described a spar may at slight additional cost be provided with a device whereby any desired curvature may be given thereto and the spar at the same time braced and stiffened.

100 Having now particularly described and ascertained the nature of the said invention and in what manner the same is to be performed I declare that what I claim is:

1. The combination with a sail-boom, of 105 means for curving the boom laterally to impart belly to the sail; said means comprising a stay secured to one end of the boom, means for projecting the stay laterally from the boom and means for tightening or slackening 110 said stay.

2. The combination with a sail-boom, of 115 means for curving the boom laterally to impart belly to the sail; said means comprising a stay secured to one end of the boom, means connected to the other ends of the stay for tightening or slackening the stay, and a lateral strut on the boom loosely engaging the stay for projecting the stay from the boom.

120 125 130 135 3. The combination with a sail-boom, of means for curving the boom laterally to impart belly to the sail; said means comprising a pair of stays secured to one end of the boom at opposite sides thereof, means extending laterally from the boom and loosely engaging the stays for projecting the stays from the boom and means connected to the other ends of the stays for tightening or slackening the stays.

4. The combination with a sail-boom, of
mechanism for curving the boom laterally to
impart belly to the sail; said mechanism comprising
5 a pair of stays having one end secured
to the boom at opposite sides thereof, means
for projecting the stays laterally from the
boom and means connected to the other ends
of the stays for tightening or slackening the
stays and constructed to slacken one stay
10 when the other stay is tightened.

5. A sail-boom of gradually tapering form
from its outer to its inner end and provided

with means for curving the boom to impart
belly to the sail.

6. A sail-boom of substantially uniform 15
height throughout its length and of gradually
decreasing width from its outer to its inner
end.

In witness whereof I have hereunto set my
hand in the presence of two witnesses.

PERCY TATCHELL.
